UNITED STATES PATENT OFFICE.

FRED R. McMURRY, OF WESTWOOD, NEW JERSEY, ASSIGNOR TO WESTERN ELECTRIC COMPANY, OF NEW YORK, N. Y., A CORPORATION OF NEW YORK.

TELEGRAPH SYSTEM.

1,324,838.

Specification of Letters Patent. Patented Dec. 16, 1919.

Application filed February 14, 1918. Serial No. 217,137.

To all whom it may concern:

Be it known that I, FRED R. McMURRY, a citizen of the United States, residing at Westwood, in the county of Bergen and 5 State of New Jersey, have invented certain new and useful Improvements in Telegraph Systems, of which the following is a full, clear, concise, and exact description.

This invention relates to telegraph systems, and particularly to printing telegraph systems.

One object of this invention is to provide a printing telegraph system with means for transmitting an auxiliary signal, whereby a 15 receiving operator may at any time break in on the transmission of a message and operate a signaling device at the transmitting station.

In the operation of printing telegraph systems it is desirable that the receiving operator be able to stop the transmission of a message and operate a signal at the transmitting station, in case it is desired to have a portion of the message repeated or for any 25 other similar reason. If no provision is made for the receiving operator to break in on the transmission of a message, it is necessary for the receiving operator to wait until the complete message has been transmitted, 30 and then signal back to the transmitting operator. Such a procedure is inconvenient and impractical inasmuch as it may be necessary in many cases to retransmit the complete message.

35 In a printing telegraph system constructed in accordance with this invention a signaling relay which is controlled by the receiving operator or operators is provided at the transmitting station for operating a signaling device and for stopping the transmission of a message. The illustrated printing telegraph system embodies a transmitting station for transmitting impulses of the same strength and polarity over a line 40 wire to a line relay at the receiving station. The various signals formed by the impulses are differentiated from each other by transmitting the impulses with various blank spaces or periods of no current 45 therebetween. The system utilized for illustrating this invention employs a five unit code made up of permutations of current impulses and intervals of no current. It is 50 to be understood, however, that the inven-

tion is equally applicable to a system in 55 which the various signals are selected by a greater or less number of impulses and intervals of no current. Potential is normally maintained on the main line, and, when the signal is to be transmitted, current is removed from the line to initiate the operation of a sunflower switch at the receiving station. The transmitting sunflower switch transmits the selected impulses at the sending station to the line wire; and the sunflower switch at the receiving station distributes the impulses received by the receiving line relay to the receiving printer. At each of the receiving stations a switch is provided for sending out stronger impulses 60 of opposite polarity to the impulses which are normally transmitted by the sending station. These impulses of opposite polarity will operate a polarized relay at the sending station, which is unaffected by the 65 impulses normally transmitted over line wires for operating the receiving line relay. The polarized relay, when operated, opens the line wire to prevent further transmission 70 of a message and operates a signaling device 75 of opposite polarity to the impulses which are normally transmitted by the sending station to call the sending operator's attention thereto.

In the system illustrated in the drawing, one sending and receiving station are illustrated, but it is to be understood that the 80 system may be provided with any number of stations and that each station may be provided with sending and receiving apparatus.

The single figure in the accompanying drawing is a diagrammatic view of a printing telegraph system constructed in accordance with this invention.

Referring to the drawing, a sending station 1 and a receiving station 2 are connected by a line wire 3 having grounded terminals. 95 The sending station 1 is provided with a suitable current-control means 4, which selects the impulses which are to be transmitted from a battery 5 over the line conductor 3 to the receiving station, a sunflower switch 6 for transmitting the selected impulses to the line wire, a sending-start relay 7 for initiating the operation of the sending and receiving apparatus, and a start-magnet 8 which is controlled by the sending-start relay 7 for initiating the operation of the sunflower switch 6.

The current-control means 4 embodies a

plurality of contact terminals 9, 10, 11, 12 and 13 which are selectively connected to a contact member 14. The current-control means 4 is also provided with a switch member 15 which is moved to engage a contact terminal 16 whenever the contact terminals 9 to 13 inclusive are operated selectively to engage the contact member 14. The switch member 15 and its associated contact terminal 16 serve for initiating the operation of the sending-start relay 7.

The sending-start relay 7 embodies an energizing coil 17, which is connected to a battery 18 by means of the switch member 15, and a holding coil 19, which is connected to a battery 20 by means of an associated armature 21. The relay 7 is also provided with an armature 22 which serves for completing a circuit from the battery 18 through the start magnet 8.

The sunflower switch 6 embodies a plurality of contact segments 24, 25, 26, 27 and 28 which are respectively connected to the contact terminals 9 to 13 inclusive and may 25 also be connected to a contact ring 29 of the sunflower switch by means of a brush 30 mounted on a rotatable brush arm 31. A brush 32 is provided for connecting a contact segment 33 to a contact ring 47 in order 30 to complete a circuit through the coil 19 of the sending-start relay 7 when the contact member 15 is operated. The brush arm 31 is frictionally mounted on a constantly rotating shaft and is prevented from rotating 35 by means of a latch 34 which is controlled by the start magnet 8.

A signaling relay 35 is provided at the sending station which is unaffected by the impulses that are transmitted over the line 40 wire 3 from the battery 5, but which is operated by stronger impulses of an opposite polarity which are received from the receiving station 2. A polarized armature 36 which is controlled by the relay 35 is adapted 45 to complete a circuit from a battery 37 through a relay 38 when operated. The relay 38 is provided with an armature 39 for completing a circuit from a battery 40 through a signaling device 41, an armature 50 42 for establishing a locking circuit for the relay, and an armature 43 for opening the line circuit 3.

The receiving station 2 embodies a selecting mechanism 50 for selecting the character 55 to be printed, a sunflower switch 51 for distributing the received impulses to the selecting mechanism, and a receiving line relay 52 which is operated in accordance with the impulses received from the sending station. 60 The selecting mechanism 50 may be of any suitable type and embodies a plurality of selecting magnets 53, 54, 55, 56 and 57 which are respectively connected to contact segments 58, 59, 60, 61 and 62 of the sunflower 65 switch 51. The contact segments 58 to 62 in-

clusive are successively connected to a contact ring 63 of the sunflower switch by means of a brush 64 mounted upon a rotatable brush arm 65. A contact ring 66 and a contact segment 67, which are bridged by a brush 68 in the initial position of the brush arm 65, are provided for completing a circuit through a start magnet 69 as will be hereinafter set forth. The start magnet 69 is provided with a latch 70 for releasing the brush arm 65 in a manner similar to the release of the brush arm 31 by the start magnet 8 at the sending station. Two contact segments 71 and 72, which are bridged by the brush 64, are provided for completing a circuit through any suitable recording or printing mechanism, as, for example, a printing magnet to record the selected character. The line relay 52 is provided with an armature 73 for connecting a battery 74 to the contact ring 63 when in an operative position, and for connecting the battery 74 to the ring 66 when in a released position.

The receiving station 2 is also provided with a switch member 75 which is adapted 90 to connect a battery 76 to the line wire 3. The battery 76, as hereinbefore set forth, is adapted to transmit stronger impulses of an opposite polarity to those which are transmitted from the battery 5 at the sending 95 station.

A line relay 45, at the sending station, may be utilized for operating a home recorder if so desired.

In describing the operation of the system 100 it is assumed that the first character of the message to be transmitted is selected by the following combination of units-current, no current, no current, no current, and current. Accordingly, the contact terminals 9 and 105 13 of the current-control means 4 are connected to the contact member 14 so as to connect the sunflower segments 28 and 24 to the battery 5. Simultaneously with the operation of contact terminals 9 and 13, the 110 switch member 15 engages the contact terminals 16 in order to complete a circuit through the sending-start relay 7. The circuit through sending-start relay may be traced from ground through the battery 18, 115 coil 17, switch member 15, contact terminal 16, contact segments 33, brush 32 and the contact ring 47 to ground. The armature 22 of the relay 7 completes a circuit for operating the start magnet 8 and the armature 120 21 completes a holding circuit for the sending-start relay which may be traced from ground conductor through battery 20, armature 21, coil 19, contact segment 33, brush 32 and the contact ring 47 to ground. It 125 should be noted, however, that the holding circuit for the start relay 7 is only maintained during the period that the brush 32 is bridging the contact segment 33 and the contact ring 47.

In the initial position of the sending sunflower switch 6, a circuit is completed from the battery 5 through the contact segment 23, the brush 30, the contact ring 29, and the line conductor 3, which maintains the relay 52 in an operative position. When the brush arm 31 is released by the latch 34, the brush 30 is rotated in a counterclockwise direction to break the circuit above mentioned from the battery 5 to the line wire 3 for releasing the line relay 52 for a purpose to be set forth hereinafter. The brush 32 disengages the contact segment 33 in order to open the holding circuit of the sending start relay 7 and permit the release of the latch 34 of the start relay 8. It is essential to release the start magnet 8 in order to prevent more than one simultaneous rotation of the brush arm 31. The brush arm 31 in its continued counterclockwise rotation successively connects the contact segments 28, 27, 26, 25 and 24 to the contact ring 29 which is directly connected to the line wire 3. Accordingly, upon engagement of the brush 30 with the segments 28 and 24, impulses will be transmitted from the battery 5 over the line wire to the receiving relay 52, and, intermediate the two impulses which are transmitted through the segments 28 and 24, three periods of no current are interposed while the brush arm 31 is rotated over the segments 27, 26 and 25.

Inasmuch as the armature 73 of the line relay 52 is released by the opening of the line wire 3 when the brush 30 disengages the contact segment 23, a circuit is completed from the ground conductor through the battery 74, armature 73, contact ring 66, contact segment 67, and the start magnet 69 to the ground conductor. The start magnet 69 is thus energized and the latch 70 is operated to release the brush arm 65. The brush arm 65 rotates in a counterclockwise direction and, when the brush 68 disengages contact segment 67, the start magnet 69 is deenergized to release the latch 70 in order to stop the rotation of the brush arm 65 when one complete rotation has been effected. The two brush arms 31 and 65 of the sending and the receiving sunflower switches are considered to be rotated substantially in synchronism with each other, so that when the contact segments 28 to 24 inclusive of the sending sunflower switch 6 are connected to the line wire 3, the contact segments 62 to 58 inclusive of the receiving sunflower switch are successively connected by the brush 64 to the contact ring 63, which in turn is connected to the battery 74 by the armature 73 whenever the line relay 52 is energized. Thus, during the rotation of the brush arm 65, a circuit is completed from the battery 74 through the selecting magnets 57 and 58 to prepare a character for printing, inasmuch as the relay 52 is operated

when the brush 64 bridges contact segments 71 and 72.

In case the receiving operator desires to communicate with the sending operator and prevent the further transmission of a message, the switch member 75 is operated to connect the battery 76 to the line wire 3. A strong impulse of opposite polarity is thereupon transmitted over the line wire 3 that operates the signaling relay 35. The armature 36 of the signaling relay completes a circuit through the relay 38, and the relay 38 in turn operates a signaling device 41 by means of the armature 39 and breaks the line circuit by means of the armature 43. When the line circuit has been broken by the armature 43 it is impossible to transmit a message until the transmitting operator opens the holding circuit of the relay 38 by means of a switch 46.

Modifications in the system and arrangement and location of parts may be made within the spirit and scope of this invention and such modifications are intended to be covered by the appended claims.

What is claimed is:

1. In a printing telegraph system, the combination with a sending apparatus, a receiving apparatus, and a line wire for connecting the same, of a line relay associated with the receiving apparatus for governing the operation thereof, a signal relay associated with the sending apparatus and responding only when impulses of a different character from those normally operating the line relay are transmitted over the line wire, a second relay controlled by said signal relay and having a holding circuit, and a signal device controlled directly by said second relay.

2. In a printing telegraph system, the combination with a sending station, a receiving station, a line wire for connecting said stations, and a signaling device disposed at the sending station, of a line relay controlled by impulses received over the line wire for governing the operation of the receiving station, and a polarized relay located at the sending station for governing the operation of the signaling device, said polarized relay being operated only by impulses of a higher voltage and of a different polarity from the impulses normally operating the line relay.

3. In a printing telegraph system, the combination with sending and receiving apparatus, a line wire for connecting the sending and the receiving apparatus, and a signaling device, of a line relay operated by impulses transmitted over the line wire for governing the operation of the receiving apparatus, a signaling relay operated only by impulses different in character from the impulses normally transmitted over the line wire for operating the line relay, and means

controlled by the signal relay for holding the line wire open and for operating said signaling device.

4. In a printing telegraph system, the combination with a sending station, a receiving station, a line wire for connecting said stations, and a signaling device, a signaling relay associated with said device, of a line relay controlled by impulses received over the line wire for governing the operation of the receiving station, a polarized re-

lay operated only by impulses of a different polarity from the impulses normally operating the line relay, and means controlled by the polarized relay for operating the signaling device through the instrumentality of said signaling relay and for holding the line wire open. 15

In witness whereof, I hereunto subscribe my name this 29th day of December, A. D., 20 1917.

F. R. McMURRY.
